UNITED STATES PATENT OFFICE.

ABRAHAM H. LEONDAR, OF ROXBURY, MASSACHUSETTS.

AUTOMATIC ALARM FOR DRIP-PANS OF REFRIGERATORS.

No. 884,828.

Specification of Letters Patent.

Patented April 14, 1908.

Application filed September 18, 1907. Serial No. 393,476.

To all whom it may concern:

Be it known that I, ABRAHAM H. LEONDAR, a citizen of the United States, residing at Roxbury, in the county of Suffolk and State 5 of Massachusetts, have invented an Improvement in Automatic Alarms for the Drip-Pans of Refrigerators, of which the following description, in connection with the accompanying drawings, is a specification, 10 like letters on the drawings representing like parts.

My invention is an automatic alarm as an article of manufacture to be sold to house-holders for them to place in their drip pans in 15 connection with the ordinary domestic refrigerator.

To this end I have mounted on a weighted base or pedestal a float device which when the pan gets nearly full of water will automatically set off an alarm.

The constructional details of my invention will be pointed out more at length in the following description with reference to the accompanying drawings.

25 In the drawings, Figure 1 shows the invention in front elevation in connection with a conventionally illustrated refrigerator whose drip pan is shown in section; Fig. 2 is a top plan view of the apparatus; and Fig. 3 shows 30 a modified construction.

It is the common practice to provide a drip pan 1 beneath the usual refrigerator 2 to receive the drippings from the drip pipe 3, and frequently the servant forgets to empty the 35 pan when it gets full, so that the water runs over on the floor and not only renders foul the area where the refrigerator stands, but tends to rot out the floor. This happens so often that it is a well recognized inconvenience attending refrigerators. A variety of 40 automatic alarm devices have been provided, most of them being expensive and more or less intricate and cumbersome. Accordingly it is the aim of my invention to provide an 45 exceedingly simple and inexpensive alarm which does not require any special kind of drip pan or of refrigerator or any attendant mechanism but constitutes in itself an article of manufacture to be sold to the householder to be simply placed directly in whatever pan may be then in use. To this end I have provided a heavy base 4 of non-corrosive metal, or it may be of iron whose surface is rendered non-corrosive, the casting 50 containing a central upright or pedestal 5 on

which is transversely journaled at 6 a rocker arm or lever 7 provided at one end with a depending leg 8 on which is mounted a float 9 of any suitable construction, preferably of cork and preferably secured by adjustable means 60 10, while at the other end the lever 7 is provided with a counterbalance weight 11 just above the push button 12 of an ordinary spring metal bell 13 such as are commonly provided on bicycles, etc., said bell being fast 65 on the post 14 of the casting. This construction is not only cheap but very sensitive, and will respond with certainty the instant the water raises the float. There is nothing to get out of order and the movement is certain, as 70 the leg 8 is rigid on the arm 7 and hence the float cannot swing to a wrong angle as might be the case if it was pivoted, the weight 11 and float practically counterbalancing each other and the bell is in position to be actuated 75 upon the slightest movement of the float. The device consists practically of four pieces, the casting, the arm and leg, the float, and the bell.

The user, having purchased the device, 80 simply sets the device into the pan, whatever shape or kind the latter may be, and the heavy base 4 keeps the apparatus in exactly correct and stable position. She then adjusts the float to correspond to the requirements of the depth of the pan. Thereafter 85 whenever the water rises sufficiently to raise the float slightly, said raising of the float depresses the weight 11 on the push button 12 of the bell, thereby causing the latter to 90 sound. The maid at once pulls out the pan from beneath the refrigerator, takes hold of the knob-like upper end of the pedestal 5 and lifts the apparatus from the pan, setting the apparatus on the floor side of the refrigerator 95 and then empties the pan. Upon returning the empty pan she again sets the alarm apparatus down in the bottom of the pan and shoves the latter under the refrigerator in place to be filled again with drippings from 100 the refrigerator.

In Fig. 3 I have shown a modification, in which instead of making the leg 8 depend rigidly from the arm 7 I have provided it as an arm or bracket 15 projecting rigidly from 105 the upright 5 and have provided a float 16 having a stem 17 sliding in a groove or hole 18 in said leg or bracket, in position to strike the overhanging end of the lever 7.

Having described my invention, what I 110

claim as new and desire to secure by Letters Patent is,

As an article of manufacture, an automatic alarm for the drip pans of refrigerators, consisting of a portable weighted horizontal base capable of maintaining the entire apparatus in stable upright position by simply resting unattached on the bottom of the pan, an upright mounted on said base, 10 an arm carried by said upright, a float carried by said arm for raising the latter when

the water rises in the pan, and an alarm bell also carried by the base in position to be engaged and sounded by said arm when the float is raised.

In testimony whereof, I have signed my name to this specification, in the presence of two subscribing witnesses.

ABRAHAM H. LEONDAR.
